SLOTTED ABRASIVE WHEEL

Harley E. Sherk, Miami, Fla., assignor to Miami Abrasive Products, Inc., Miami, Fla., a corporation of Florida

Application August 21, 1933, Serial No. 686,077

3 Claims. (Cl. 51—206)

This invention relates to abrasive wheels having alternately disposed non-grinding areas and grinding surfaces.

More specifically, this invention relates to abrasive wheels having slotted grinding faces to form alternate cutting edges and grinding surfaces and permit the self-elimination of abraded particles.

I have found that the efficiency and grinding capacity of abrasive wheels can be greatly enhanced by the provision of spaced slots in the grinding surface of the wheel to form a plurality of grinding surfaces in spaced relation from each other. The slots create non-grinding areas adjacent the grinding surfaces of the wheel and thereby greatly reduce friction and heating during the grinding operations since the material being ground is not subjected to a steady and constant grinding. In addition, the slots carry air which aids in cooling the material being ground.

The sharp edges formed in the grinding face by the slots impart a milling or cutting action as the material being ground passes over the slots and contacts these edges. This action coupled with the usual grinding action of the grinding faces forms an abrasive wheel with high capacity.

The slots also act to eliminate abraded particles which normally are withheld in the abrasive grinding surface and in addition, by effecting an intermittent grinding operation do not permit the abraded particles to form "streaks" around the wheel.

It is, therefore, an object of this invention to provide abrasive grinding wheels having alternate areas of nongrinding spaces and grinding surfaces.

Another object of this invention is to provide a slotted abrasive wheel.

Another object of this invention is to improve the grinding efficiency of abrasive wheels by forming the wheels with alternately disposed cutting edges adjacent to the grinding surfaces.

Another object of this invention is to provide a self-cleaning abrasive wheel.

Another object of this invention is to form abrasive wheels with intermittent grinding surfaces to reduce friction and eliminate overheating of the material being ground.

Other and further objects of this invention will be apparent to those skilled in the art from the following specification and annexed drawing which form a part of this specification.

On the drawing:

Figure 1 is a side elevational view of a slotted abrasive wheel according to this invention in which the grinding surfaces are on the periphery of the wheel.

Figure 2 is an end elevational view, partly in

cross section, of the grinding wheel shown in Figure 1 taken substantially along the line II—II of Fig. 1.

Figure 3 is a front side elevational view of a hollow cylinder form of abrasive wheel slotted on a flat face according to this invention to form a flat slotted grinding surface.

Figure 4 is a view, partly in cross-section, taken substantially along the line IV—IV of Figure 3.

Figures 5 to 8 are plan views of grinding surfaces according to this invention showing alternative forms of slot designs in the surfaces.

As shown on the drawing:

In Figures 1 and 2, the reference numeral 10 indicates an abrasive wheel formed from any abrasive material, such as silicon carbide, emery, carborundum, glass, or any natural or artificial abrasive or combination thereof. The abrasive material may be in grain form and molded in any bonding material, such as bakelite. Since this invention deals with the formation of slots or alternately disposed non-grinding spaces adjacent the grinding surfaces of abrasive wheels, it should be understood that any materials normally used for forming abrasive wheels can be used.

The abrasive wheel 10 is provided with an opening 11 in the center thereof for receiving a bushing 12 which permits the mounting of the wheel onto a driven shaft. The bushing 12 is usually molded into the opening 11 to form an integral connection between the grinding wheel and the driven shaft.

The periphery of the wheel 10 is provided with a plurality of parallel slots 13 in spaced relation from each other extending transversely across the periphery. The slots 13 extend into the wheel for a considerable distance below the outside periphery but, as may be readily appreciated, the depth of the slots is limited by the strength of the abrasive material forming the wheel, it being evident that a relatively soft material would crumble and break off. If a soft material is used, the slots are relatively shallow.

The slots 13 form radially extending teeth or intermittent portions 14 around the periphery of the wheel. Each tooth 14 has a grinding surface 15 on its outer periphery. In addition to the grinding action of the surfaces 15, the sharp edges of the teeth permit a milling or cutting action during the grinding operation.

As shown in Figures 3 and 4, the reference numeral 20 indicates a hollow cylindrical form of grinding wheel provided with slots 21 in a flat face of the wheel so as to form intermittent grinding portions 22 in addition to a grinding surface 23 on the periphery of the wheel. The slots 21 have the same cooling and cleaning action on the flat grinding surfaces 22 as the slots 60

13 have on the peripheral grinding surfaces 15 shown in Figures 1 and 2.

As shown in Figures 3 and 4, the abrasive wheel 20 is of a hollow cylindrical form with an opening in the center for receiving a bushing 24 which is integrally bonded to the abrasive material. As shown in Figure 4, the bushing 24 terminates short of the flat grinding surfaces 22 so as not to interfere with the grinding operation. A driven shaft 25 may be inserted in the hollow bushing 24. The bushing 24 is detachably secured to the shaft in any suitable manner.

The grinding surfaces shown in Figure 5 are formed in a checkerboard arrangement in which 15 the slots adjacent the grinding surfaces are rectangular or cube-shaped and do not extend across the entire flat surface or periphery of the wheel. This design may sometimes be desirable to form a more solid wheel.

20 As shown, the grinding surfaces 30 are in the form of rectangular portions each of which is separated from a corresponding rectangular portion in the same row by a slot 31, which touches the corners of two grinding portions in an adjacent row since the slots 31 extend only half-way across the grinding wheel. The slots 31 and the grinding surface portions 30 are of substantially 25 the same width.

30 In Figure 6, a grinding surface 40 is provided with transversely extending slots 41 which are offset at the center of the grinding wheel and extend to the opposite side of the wheel in an offset position. This design effects a very strong 35 construction since the staggered arrangement of the slots distributes the stress on any cutting edge of a grinding portion over a greater area. The slots 41 are approximately half the width of the grinding portions 40 and extend about half way through the thickness of the wheel. This 40 form of design may be referred to as a staggered slotted abrasive wheel.

In Figure 7, diagonal grinding surfaces 50 are formed by diagonal slots 51 extending across the width of the wheel. The slots 51 are substantially 45 identical with the slots 13 shown in Figure 1 or with the slots 21 shown in Figure 3 except that they extend diagonally across the grinding face instead of transversely across the face.

50 In Figure 8, slots 61 are formed in V-shape to form V-shaped grinding portions 60. The points of the V-portions 60 are preferably at the center of the grinding face. The V-portions have desirable characteristics in some grinding operations, and act as plows for throwing the abraded 55 particles outwardly from the material being ground.

From the above description, it is evident that this invention includes grinding wheels having 60 slots in their grinding surfaces which may be of many different forms or designs, such as the straight transverse slots shown in Figures 1 to 4, the checkered slot arrangement shown in Figure 5, the staggered slot arrangement shown in Figure 6, the diagonal slots shown in Figure 7 or the V-shaped slots shown in Figure 8. The provision 65 of slots, such as are shown, eliminates a large percentage of friction during the grinding operation and when formed on peripheral grinding faces creates a milling action in addition to the usual straight grinding operation because of the sharp edges which are formed adjacent the slots.

70 When the abrasive wheel is revolving during the grinding operation, air is carried by the slots and directed against the material being ground.

The air has a cooling action and is highly desirable.

In the normal grinding operations on abrasive wheels there is a strong tendency for the abraded particles to remain on the surface of the wheel. Often, these particles are reground between the material being ground and the wheel thereby causing scratches and tending to glaze the wheel and retard the cutting. The slotted portions on wheels of this invention act as cleaners and cause 10 the removal of the abraded particles since these particles are naturally thrown into the slots from which they are removed by the velocity of the wheel.

The slotted grinding wheels may be made in any 15 desired size. I have formed some of the slotted wheels in accordance with this invention of a size small enough for dentists to use in grinding teeth. The cooling action created by the slots eliminates much of the heat that is generated 20 during the grinding operation with the present type of dentist's wheel. Furthermore, the slots permit the wheel to remain in true shape for a longer period of time.

25 Slotted wheels of my invention are particularly adapted for shoe making and shoe repair work because abraded leather particles are readily removed from the wheel by the slots.

It should be understood that the abrasive 30 wheels of this invention have pre-formed slots therein which are as deep as the strength of the molding material bonding the abrasive particles together will permit. These pre-formed slots are not to be confused with burred surfaces such 35 as are cut into grinding wheels to sharpen the same after use.

I am aware that many changes may be made and numerous details of construction may be varied through a wide range without departing from the principles of this invention, and I, 40 therefore, do not purpose limiting the patent granted hereon otherwise than is necessitated by the prior art.

I claim as my invention:

1. An abrasive wheel comprising a cylindrical 45 member having a flat face and an aperture extending therethrough, staggered grinding surfaces formed in said face by slots extending radially from the aperture half-way to the outside periphery of the cylinder and offset at the half-way mark to extend to the periphery in an offset portion.

2. An abrasive wheel having a peripheral grinding surface, said grinding surface being divided into a plurality of rectangular surfaces in spaced 50 relation from each other, said surfaces being in staggered relation with rectangular slots extending transversely therebetween from one face of the wheel to the middle of the periphery thereof and being offset at the middle of the periphery 55 to extend to the other face of the wheel in an offset relation to said first mentioned slots, and means for securing the wheel to a driven shaft.

3. An abrasive wheel comprising a body portion having an annular cross section in a plane at 60 right angles to its axis of rotation, a plurality of teeth extending outwardly from the body portion and presenting at their outer ends grinding surfaces in staggered relation, said teeth being separated in a circumferential direction by transverse slots having portions offset in a direction circumferentially of said wheel.

HARLEY E. SHERK.
